(57) **CLAIM**

The ornamental design for a floor structure of a materials handling vehicle as shown and described.

DESCRIPTION

FIG. 1 is a perspective view showing a first embodiment of a floor structure of a materials handling vehicle as seen from the top, front, and first side;

FIG. 2 is a perspective view thereof as seen from the bottom, back, and second side;

FIG. 3 is a front elevation view thereof;

FIG. 4 is a back elevation view thereof;

FIG. 5 is a first side elevation view thereof;

FIG. 6 is a second side elevation view thereof;

FIG. 7 is a top plan view thereof;

FIG. 8 is a bottom plan view thereof;

FIG. 9 is a perspective view showing a second embodiment of a floor structure of a materials handling vehicle as seen from the top, front, and first side;

FIG. 10 is a perspective view thereof as seen from the bottom, back, and second side;

FIG. 11 is a front elevation view thereof;

FIG. 12 is a back elevation view thereof;

FIG. 13 is a first side elevation view thereof;

FIG. 14 is a second side elevation view thereof;

FIG. 15 is a top plan view thereof; and,

FIG. 16 is a bottom plan view thereof.

Each stippling pattern shown in FIGS. 1-16 is used to represent a different color, e.g., contrasting colors of the floor structure of a materials handling vehicle. That is, one stippling pattern represents a first color, and the other stippling pattern represents a second color, different from the first color.

The broken lines in the drawings depict portions of the floor structure of a materials handling vehicle that form no part of the claimed design.
